CARBURETOR

Filed Nov. 12, 1925

INVENTOR

Peter Gwisdalla

BY

Thomas Donnelly
ATTORNEY.

UNITED STATES PATENT OFFICE

PETER GWISDALLA, OF DETROIT, MICHIGAN, ASSIGNOR OF ONE-FOURTH TO AUGUST POLK AND DOMINIC S. POLK, BOTH OF RUTH, MICHIGAN, ONE-FOURTH TO JOSEPH FOLTA, OF PARYSVILLE, MICHIGAN, AND ONE-FOURTH TO JOHN B. SOSNOWSKI, OF DETROIT, MICHIGAN

CARBURETOR

Application filed November 12, 1925. Serial No. 68,521.

My invention relates to a new and useful improvement in a carburetor and has for its object the provision of a carburetor which will be simple in structure, economical of manufacture, and highly efficient in use.

Another object of the invention is the provision in a carburetor of means for simultaneously opening the air ports and the fuel port proportionately to each other.

10 Another object of the invention is the provision in a carburetor of a valve arrangement for controlling the admission of air and fuel to the interior of the carburetor and so arranged through the use of springs as to cause 15 an opening and closing of these control means upon the unequal pressure being developed within the carburetor and the air intake pipe.

Other objects will appear hereinafter.

20 The invention consists in the combination and arrangements of parts hereinafter described and claimed.

The invention will be best understood by a reference to the accompanying drawings 25 which form a part of this specification and in which,

Fig. 1 is a central vertical sectional view of the invention, and,

Fig. 2 is a sectional view taken on substantially line 2—2 of Fig. 1.

The invention in its preferred form comprises a shell 7 having a base 8 threaded thereon by means of threaded flange 9. The base is provided with a flange 10 which rests 35 against the lower surface of the shell 7. An air intake pipe 11 communicates with the shell 7 and an outlet pipe 12 also communicating with the shell 7 serves to deliver the mixture of fuel and air to the manifold of 40 the engine with which used. A butterfly valve 13 is provided in the air intake pipe 11 and a similar butterfly valve 14 is provided in the outlet pipe 12 which carries an arm 15 for operating the valve 14. Con-

45 nected to the valve 13 is an arm 16 upon which is mounted a link 17. A suitable rod 18 is connected to the link 17 for operating the valve 13. Connected to this link 17 is a rod 19 which is also connected to an arm 50 20 fixedly attached to a bar 21 so that upon

operating the valve 13 the bar 21 is caused to rock.

A cap 22 is mounted on the shell 7 by means of suitable bolts 23, suitable gaskets, or packing, 24 being interposed between the 55 shell 7 and the cap 22. The cap 22 is provided with an enlargement 25 so as to afford a chamber in which is positioned a spring 26, one end of which is attached to an adjusting screw 27. The other end of the 60 spring 26 rests against a valve head 28 which is adapted to seat in a valve seat formed in the upper end of the gland 29 which is threaded into the cap 25. This valve head 28 is fixedly mounted to a rod 30 which projects through an opening formed in the gland 29 and is provided intermediate its ends with a nut 31 fixedly attached thereto. A cylindrical valve guide 32 is threaded into the 65 shell 7 and provided with a peripheral flange 70 35 which serves as an abutment to prevent an undue threading of the chamber 32 into its position. This chamber 32 is provided at the upper end with a series of notches 33, 33' and 33''. Slidably mounted in the 75 member 32 in loose relation to the rod 30 is a valve 34 adapted for a snug fit to the interior of the member 32 so as to prevent the passage of air around the sides thereof. Mounted on the rod 30, in an embracing relation, intermediate the member 31 and the member 34, is a spring 36. Screwed to the lower end of the rod 30 is a nut 37 supporting a suitable washer engaged against which is one end of a spring 38, mounted in an embracing relation on the rod 30 and having the other end in engagement with the member 34.

A yoke 39 is fixedly mounted to the bar 21 by means of arms 40. This yoke 39 embraces the rod 30 intermediate the spring 36 and the nut 31 so that upon rocking the member 21, the valve 34 is moved relatively to the member 32.

The cap 22 is provided with a fuel inlet 95 41 which communicates with the chamber in the raised portion 25. The communication of this member 41 is controlled by a needle valve 43 mounted on a stem 42 and provided with a head 44. A suitable nut 45 is threaded 100

on the stem 42 for retaining the member 43 in position.

The construction is such that when the needle valve is opened to permit the passage of fuel into the interior of the member 25, the valve 28 will then prevent its passage into the interior proper of the carburetor. As the engine with which the carburetor is used is started, the suction causes the member 34 to rise in the member 32 sufficiently to clear the notches 33, thus providing a port through which the air may enter into the interior of the carburetor. At the same time the valve 28 is raised from its seat permitting the fuel to enter the interior of the carburetor and become mixed with the air. The action of the springs serves to close these ports as soon as the suction of the engine is released.

In order to prime the engine, that is, to permit fuel to the carburetor for its delivery to the engine without the mixture of any air, the valve 13 is closed by means of the rod 18. At the same time that this valve is closed, the member 34 is raised upwardly and through the rod 30 the valve 28 is moved from its seat.

It is to be noted that the link 17 is provided with sufficient clearance so that the valve 13 will not be closed at each movement of the valve 34 when the engine is in operation.

It is also apparent from the description and the drawing that the carburetor is a floatless carburetor so that the disadvantages and difficulties resulting from the operation of the carburetor float are dispensed with and a more efficient carburetor, on this account, provided. The carburetor, because it is floatless, is particularly adapted for use with aeroplanes, in the operation of which the engine is sometimes inverted and quite frequently inclined at a considerable angle to the horizontal.

While I have illustrated and described the preferred form of construction, I do not wish to limit myself to the precise details of structure set forth, but desire to avail myself of such modifications and variations as come within the scope of the appended claim.

Having thus described my invention what I claim as new and desire to secure by Letters Patent is:

A carburetor comprising a shell having a fuel inlet port; an auxiliary chamber adapted for communication with said inlet port and with the interior of said shell; a cylindrical member fixedly mounted in said shell; a disc slidably mounted in said cylindrical member, the upper end of said cylindrical member being provided with axially extending notches formed therein; a valve for closing communication of said auxiliary chamber with said shell; a stem on said valve projecting through said disc; a collar fixedly mounted on said stem, intermediate its ends; a spring engaging at one end with one face of said disc, and at the other end with said collar; a spring

mounted on said stem in embracing relation, engaging at one end the opposite face of said disc; a washer mounted on said stem engaging the opposite end of said last mentioned spring; a spring mounted in said auxiliary chamber engaging said valve and normally thrusting the same to closed position; and a rockably mounted fork engaging said collar for moving said disc and said valve in unison with each other, the engagement of said springs with said disc effecting the movement of said disc in either direction upon sufficient pressure exerted through said springs against said disc.

In testimony whereof, I have signed the foregoing specification.

PETER GWISDALLA.
